TYPEWRITING MACHINE

Harry C. Yaeger, West Hartford, Conn., assignor
to Underwood Corporation, a corporation of
Delaware

Application December 30, 1942, Serial No. 470,677

39 Claims. (Cl. 197—177)

This invention relates to typewriting machines and with regard to more specific features thereof to tabulating devices therefor, particularly to such tabulating mechanisms embodying tabulating stops which are projectable to, and retractable from, tabulation-controlling positions by the employment of power agencies.

The general object of the invention is to provide a reliably operative, easily serviceable and simple, power-actuated tabulating mechanism for typewriting machines.

It is another object of the invention to provide a power tabulating mechanism having the above merits which embodies resiliently active power means for projecting tabulating stops to tabulation controlling positions.

Another object of the invention is to provide a power-actuated tabulating mechanism, particularly suitable for denominational tabulating, embodying efficient and simple means whereby the stops, upon projection, remain reliably projected pending the termination of the tabulating movement as controlled by the projected stop.

A further object of the invention is to provide, in a power-actuated tabulating mechanism having resilient stop-projecting means, positive, simple and efficient, power-actuated retracting means which become effective automatically as the carriage is arrested under the control of the projected tabulator stop.

It is also an object of the invention to provide, in combination with the novel tabulating mechanism herein featured, an efficient and simple palm-key device under control of which one of the group of tabulating stops is efficiently projectable.

It is another object of the invention to provide means whereby the tabulating stops are not liable to obstruct return travel of the carriage when the latter reaches or is stationed in its extreme line-end position.

A still further object of the invention is to provide, in combination with the present novel tabulating mechanism, certain devices which provide for the automatic retraction of any projected tabulator stop when the carriage reaches a line-end position defined by a margin stop, wherefore the carriage is then unobstructed in its return movement.

Also an object of the invention is to provide a tabulating mechanism in which a relatively great number of tabulator stops are selectively projectable from the keyboard through a greatly reduced number of controlling connections, so that other mechanisms in the machine are more

accessible for inspection and repair than would be possible otherwise.

Other objects will be in part obvious, and in part pointed out particularly as the following description of two preferred embodiments of the invention proceeds.

In the accompanying drawings:

Figure 1 is a skeleton front-perspective view of the new tabulating mechanism.

Figure 2 is a right-hand side view of a typewriting machine embodying the tabulating mechanism of the present invention, portions of the machine, especially almost all of a right side wall, having been broken away for more clearly illustrating the invention.

Figure 3 is a fragmentary front elevation, showing a series of denominational tabulator stops and a housing therefor one of the tabulator stops being shown projected and the carriage having been intercepted by this stop.

Figure 4 illustrates in right side elevation, a part of a tripping mechanism shown in Figures 1 and 2, in an operated state suppressing repeat tabulation.

Figure 5 illustrates in right side elevation a mechanism whereby in response to the conclusion of a tabulating run of the carriage a projected tabulator stop is automatically retracted by power, the mechanism being in an operated state.

Figure 6 is also a right side elevation and shows one of a series of tabulator stops spring-moved to projected position under control of one of a series of tabulator keys.

Figure 7 shows the tabulation stripping mechanism of Figure 4 modified to provide for repeat tabulation.

Figure 8 is an exploded diagrammatic front-perspective view illustrating a key controlled permutation mechanism by means of which the various tabulator stops may be selected for projection.

Figure 9 is a front perspective view showing in separated relation two parts of a comb and bracket structure serving to support and guide certain parts of the tabulating mechanism.

Figure 10 is a front perspective illustrating the supporting structure for the tabulating keys, and separated therefrom, a separable unit including certain parts of the aforesaid permutation device.

Figure 11 is a fragmentary front view in which the carriage is in line-end position and in which, in consequence thereof, a lever has been operated to cause a stop retraction operation in the machine.

Figure 12 is a fragmentary front view showing

the denominational stops of Figure 3 in their normal positions and showing the carriage in an absolute line end position.

Figure 13 is a side view similar to Figure 2, but depicts a modified form of the invention wherein each tabulator stop is releasable for projection by an associated tabulator key by direct control.

Referring now more in detail to the drawings, left and right side walls 10 of a typewriting machine, support a trackway 11, whereupon a platen carriage 12 is adapted to travel, the carriage being provided with a rail 13, the latter of which rolls upon said trackway 11 by means of anti-friction rolls 14. A letter-feed escapement of usual manufacture, designated in Figure 2 by the reference numeral 15, normally restrains the carriage 12 against advance movement by a spring motor 16, through the medium of a draw band 17 which is attached to the carriage rail 13, see Figure 1. Said escapement 15 includes a dog 18 which is normally in carriage movement controlling engagement with an escapement wheel 20, the latter of which, together with a shaft 21 and a pinion 22, is unitarily rotatable in brackets 23 and 24 secured to the general framework of the machine. The said pinion 22 meshes a rack 25 on the carriage and it will be seen from the aforesaid that the escapement 15 is normally in control of the carriage.

Extending along the rear of the carriage and carried thereby is a rack 26 which supports a series of column-defining tabulator stops 27, preferably key-settable. Underneath these column-defining stops 27 there are arranged in closely adjacent relation a plurality of denominational tabulator stops in the form of slidable blades or reeds 30. All the stops 30 are normally positioned as shown in Figure 2, that is, they are normally out of tabulation controlling range with the column-defining stops 27.

The blades or reeds 30 are made of thin stock and are guided for vertical movement in open slots 31 provided in a bracket or comb plate 32, see Figures 2, 3, and 9, another bracket 33 being superposed upon the bracket 32 and a bar portion 34 thereon closing up the front ends of the slots. Both the brackets 32 and 33 are secured to the under side of a rear wall 35 of a housing 36 wherein the stop reeds 30 are accommodated. At their upper ends, the reeds protrude through a rectangular opening 37 provided in a top-plate 38 constituting part of the housing 36. The upper ends of the reeds 30 fit slidably between front and rear edges of the top-plate at the opening 37 and the latter is of sufficient length to give the upper ends of the stop reeds capacity for some movement in parallel to the direction of the carriage travel, for a purpose which will be stated later. Each reed or blade 30 has riveted or otherwise secured to its left side a thin spacer plate 39 and the reed and spacer plate assemblies are normally compacted against each other rightwardly against an edge of the top-plate at one end of the opening 37, in a manner to be set forth later. The thickness of each reed together with its spacer plate equals a letter-feed space.

Associated with each stop reed 30 and attached to rearwardly reaching branches 40 thereof are contractile springs 41 which urge the stop reeds 30 upwardly, thereby to project their upper ends into tabulation controlling range with the column stops 27. However, in order that a desired stop reed 30 may move to an effective projected position, a bail 42 must be elevated and a permuta-

tional blocking mechanism for the reeds 30, generally designated by the reference character 43, must be selectively operated.

Primarily the bail 42 serves to retract the stop reeds 30 whenever a tabulation is being concluded and, preferably, for reasons to be pointed out later, is releasably detained in its lowered position following its stop-retracting movement. As best seen in Figure 1, the bail 42 comprises a straight bar portion 44 which overlies ledges 45 integral with the lower ends of the reeds 30, and two side arms 46 which reach forwardly from the bar portion 44. At the front the bail 42 is stiffened by a rod 47, and together therewith pivots on a rod 48 carried by and extending intermediate the side walls 49 of the housing 36. A pitman 50 articulated at opposite ends to the rod 47 and to an arm 51 fastened on a transverse shaft 52, oppositely connects the latter with the bail. The shaft 52 is rockable within the framework of the machine and at its right end has fastened thereto a pendent arm 53 of which a bent-off tongue 54 normally bears against the rear end of a fore-and-aft extending latch lever 55, the arm 53 being urged forwardly under the tension of a spring 56 exerting always an upward pull on the bail 42. See Figures 1 and 2. The said latch lever 55 is pivoted intermediate its ends at 57 to a bracket plate 58 having front and rear ends oppositely located in slots provided respectively in pivot rod supporting members 59 and 60 of the machine, the respective rods 59 and 60 of which serve to anchor the bracket 58 securely to said members. Upon depression of any one of a series of denominational tabulator keys 65, in a manner to be set forth in detail later, the latch lever 55 is rocked counterclockwise from the Figure 2 to the Figure 6 position, the tongue 54 being thereby freed for forward movement, thereby allowing the bail 42 to rock, wherefore all the reeds 30 are free to rise in so far as the bail is concerned. However, the aforesaid stop blocking mechanism 43, under selective control of the depressed tabulator keys 65 is then effective to block all but the desired reed 30 against projection, the result being that only the desired reed will become projected. The said blocking mechanism 43 comprises horizontally disposed slides 61, 62, 63, and 64 arranged behind each other, all overlying the said rearward branches 40 of the stop reeds and each having a set of differently disposed notches 67, whereby, upon operation of different ones or different combinations of these slides, different individual stop reeds are free to rise to tabulation controlling positions, it being understood that a reed in order to rise must be free to enter a notch 67 in every one of the slides. In the arrangement illustrated in Figure 8, the various denominational reeds 30 from left to right, beginning with the leftmost one, that is, the one of the lowest denominational order, are free to rise upon the respective operations of the slides, 61, 62, 63, 64, 61 and 62, 61 and 63, 61 and 64, 62 and 63, 62 and 64, and 63 and 64. The notched slides underlie the bracket plate 32, and flanges 68, bent downwardly at spaced locations from the plates 32 and 33, provide rear and bottom guides for the slides. The reeds 30 serve to retain the slides at the front and for reducing the frictional contact between the notched slides, the latter have protuberances 70 which are instrumental to provide large clearance areas therebetween. At their right ends, each slide 61, 62, 63, 64, has two vertically opposite extensions 71, and to one of which on each stop there is at-

tached a spring 72 for restoring its associated slide rightwardly to a normal position, the latter of which is defined by the upward extension 71 engaging a stop edge 73 provided by a cut-in on the bracket plate 33.

The mechanism by which the slides 61, 62, 63, and 64 are selectively operable by the tabulator keys 65 will now be described. Each tabulator key 65 comprises a bell crank 74 and these bell cranks are pivoted upon a common pivot rod 75 which extends transversely of the machine through ears 76 reaching upward from the cross members 60, the various ears being formed by transversely slotting an elongate top-ridge of the cross member 60, and the bell cranks 74 being guided for vertical operation between the said ears. Each bell crank 74 includes an upwardly reaching arm 77 disposed behind a series of superposed elongate plate members 81, 82, 83, and 84, all extending along the rear of the array of tabulator keys and all being movable in horizontal planes. As best seen in Figures 1 and 10, each of said plates 81, 82, 83, and 84 is restrained for bodily movement fore and aft by two levers 85 arranged end to end intermediate a rectangular, elongate clearing 86 of the associated plate. The levers 85, where meeting end to end, have toothed connections 87, and the other ends of the levers have toothed connections 88 with their associated plates at the ends of the said clearings 86. The said levers 85 are pivotally carried upon a narrow transverse shelf 90 by means of shoulder screws 91, spacing washers 92 being provided on said screws intermediate the levers and also intermediate the lowermost levers and the shelf. Each of said plates has secured thereto, by spot welding or otherwise, at the underside, at the region of the toothed connections 88, a leaf 93; and as is evident from Figures 1 and 10, the lever-ends thereat overlie the leaves 93 thereby to keep the plates permanently linked to the levers 85. It may be noted here that all the levers 85 are identical in form and that their spacing leaves 89 may be interposed between the toothed connections 87 of the respective pairs of levers, each of the leaves 89 preferably being spot welded or otherwise bound to one of the pairs of levers 85. See Figure 10. The shelf 90, together with the said plates and the levers 85, comprises a unit 94, see Figure 10, which is fastened by means of nuts 95 and pendent studs 96 on the shelf 90, to a plurality of mounting lugs 97 which are integral with the cross member 60. Taking note of the various notches 100, provided along the rear edges of the plates 81, 82, 83, and 84 (see Figure 8), it will be seen that different ones or different combinations of these plates are adapted for bodily forward displacement by the individual bell crank arms 77 of the tabulator keys 65. The arrangement of the notches is such that the operation of the plates 81, 82, 83, 84, 81 and 82, 81 and 83, 81 and 84, 82 and 83, 82 and 84, and 83 and 84 is effected respectively, under control of the various tabulator keys 65, beginning with the lowest and ending with the highest denominational order. The four plates 81, 82, 83, and 84 are respectively connected to the four reed blocking slides 61, 62, 63, and 64 by Bowden wire cables 101, 102, 103, and 104 and bell cranks 105 associated with said cables, the latter engaging lugs 106 on the slides. The said cables comprise flexible casings 107 wherein wires 108, constituting flexible links, are slidable, one end of each wire being connected to one of the narrowed right ends of the plates 81, 82, 83, and 84, and

the other ends being attached to the several bell cranks 105 which, as seen in Figure 3, are pivoted upon a stud 114 reaching downwardly from the bracket 33. At their front ends, see Figure 10, the casings 107 extend into and are anchored by screws 111 in an upright boss 112 of the shelf 94, while the rear ends, see Figure 3, are similarly anchored in a block 113 fast on a downwardly bent branch 116 of the bracket 33. The said cables are thin and flexible; and since they are fewer in number than the tabulator keys, they are easily accommodated in the machine embodying a great number of tabulator keys. Furthermore, the cables may be conveniently shifted for access to other mechanisms. In the embodiment of the invention shown, the cables lie close to the right side wall of the machine and thus leave the center of the machine free for accommodating the typing mechanism, not shown.

The tabulator keys 65 are limitedly operable to equal extents and, referring particularly to Figures 1, 8, and 10, it is evident that the plates 81, 82, 83, and 84, due to their differing locations, from the pivot wire 75, are operated to different extents, the lowermost plate 81 receiving the smallest motion. On the other hand, it will be seen that the uppermost bell crank 105 operates upon its associated slide 84 nearest to the pivot stud 114, and that the progressively lower bell cranks 105 operate upon their respectively associated slides at progressively more distant points. The entire arrangement is such that the differing motions received by the plates 81, 82, 83, and 84, and transmitted by the wires 108, are translated into slide motions of equal magnitude.

The aforesaid springs 72 acting upon the slides 61, 62, 63, and 64 tend also to return the plates 81, 82, 83, and 84 to normal positions, and are assisted in this by a spring member 118 secured to the front edge of the shelf 94 and having oppositely branching leaves bearing upon the several plates. Contractile springs attached to the bell cranks 74 serve to restore the tabulator keys 65, and it will be perceived from Figure 10 that the upper ends of these springs are attached to a common anchorage rod 121 lying in a groove 122 of the shelf 94, clearances 123 for the springs being provided in the shelf.

Reviewing the connections between the keys 65 and the blocking slides 61, 62, 63, and 64, it will be seen that the tabulator reeds 30 of the various denominational orders are free to rise upon depression of tabulator keys of corresponding orders.

As has been previously stated, the latch lever 55 is rocked counterclockwise to the Figure 6 position when any one of the tabulator keys is operated and to this end a lever 124, pivoted upon the aforesaid rod 75 and located between two ears 125, is operable by any of the plates 81, 82, 83, and 84; and when so operated, acts upon an arm 126 which overlies the front end of the latch lever 55, the latter moving then to the Figure 6 position and remaining there during tabulator key operation. Therefore, upon operation of any tabulator key 65, the corresponding tabulator reed 30 will rise because the bail 42 permits rise of any reed that is permitted to rise by the slides 61, 62, 63, and 64.

The bail has an arm 127 having an articulation with a lever 128 which is pivotally carried on the framework of the machine and which is adapted to throw the escapement dog 18 clear of the escapement wheel 20 upon upward movement of the bail 42. The carriage is thus released to the in-

fluence of the spring motor 16 when any one of the tabulator keys 65 is depressed, and will consequently advance leftwardly until one of the carriage-borne tabulator stops 27 is intercepted by the projected tabulator reed 30.

At this point, it should be remembered that the reeds 30 are normally crowded against the right end of the opening 37 and are capable of some leftward displacement. Thus, since operation of any tabulator key causes the carriage to be drawn leftwardly by the motor 16, it follows that any projected stop reed, together with whatever reeds are leftward thereof will be displaced leftwardly by the engaging carriage-borne stop 27. Bearing rightwardly against the leftmost reed 30 is an upright arm 130 of a three-armed pivoted member 131 which receives a counter-clockwise motion whenever any of the projected reeds is displaced leftwardly, and it is responsive to receipt of this motion that the projected reed is caused to be retracted automatically by power.

As shown in Figure 3, said displacement of the reeds 30 is adjustably limited by a screw 129, the object being to effect the arrest of the carriage in positions wherein the letter feed mechanism is adapted to assume definite control. According to the embodiment of the invention shown, said power retraction is effected through a power mechanism comprising a continuously motor-driven fluted shaft 132 whereto an actuator 133 bearing a toothed element 134 is adapted to be transitorily connected in order that a reed-retracting motion be transmitted to the said bail 42.

The said actuator 133 is pivotally connected at its front end on a pendent arm 135 which is swingable fore and aft on a pivot rod 136 pivoted upon a cross member 137 of the machine, the cross member having a slot 138 to accommodate and guide the arm. As seen in Figure 2, the actuator is normally raised clear of said fluted shaft 132 against an angular bar 141 by a spring 142 which is anchored to the bar and so disposed as to urge the actuator also rearwardly. Normally, as seen in Figure 2, the said pendent arm 135 bottoms in the slot 138. The said motion of the three-armed member 131 received incidental to the displacement of the projected reed, is transmitted over a link 143, a pivoted lever 144, another link 145, a pivoted bail 146, another lever 147, and a hook-shaped member 148, to the said actuator 133, in a manner to draw the toothed element 134 thereon into engagement with said fluted shaft 132, the result being that the said fluted shaft 132, after first imparting a limited pivotal movement to the toothed element 134, will bodily displace the latter and the actuator forwardly. This brings about the restoration of the bail 42 through the intermediary of a short link 151 and an arm 152, the latter of which may be integral with the arm 53 and fast therewith on the shaft 52. The mechanism just described provides for the restoration of the reeds in a reliable and positive manner and it will be observed that no delicate and costly mechanism is employed to maintain the reeds projected during the tabulations.

Obviously the pivotal lost motion of the toothed element 134 on the actuator link 133 delays the power retraction of the projected reed or blade 30, so that some time passes between the displacement of the projected tabulator reed and the actual retraction thereof effected by operation of the bail 42. It is to be understood that the retraction of the reed is effected only after

said reed or blade has intercepted the carriage in its tabulating run.

As is evident from Figure 5, the arm 53 is restored a little beyond the normal position shown in Figure 2, at which time the toothed element 134 is forced upwardly out of driving engagement with the fluted roll through engagement of a downwardly reaching actuator projection 153 by a tooth of the fluted shaft. As the toothed element is forced clear, the said actuator spring 142 will lift and return the actuator to normal position, a pin-and-slot connection 154 being provided intermediate the actuator and the link 151 to allow such restoration independently of the arm 53, and, therefore, the bail 42. As the bail 42 is restored, the arm 53 moves rearwardly; and either the said latch lever 55 or a secondary latch 155, or both successively, will detain the arm 53 until another depression of the tabulator key is effected. If the operator releases the tabulator key before the power restoration of the bail is effected, the rear end of the latch lever 55 will descend in front of the tongue 54 on the arm 53 and thereby will hold the bail against upward movement. On the other hand, in the event the operator should maintain the tabulator key depressed, the said secondary latch 155, which may be pivotally carried on the lever 55, will be in a position to prevent forward movement of the arm 53. A spring 156 is attached to the latch 155 in a manner to urge its latching end upwardly against the latching lever 55 and to exert simultaneously a restoring influence on the latter. Normally, as seen in Figures 1 and 2, the extreme rear end of the secondary latch 155 lies underneath the tongue 54 and permits the latter to swing forwardly upon tabulator key operation, the latch 155 being yielding, as shown in Figure 6. If, upon restoration of the bail 42, a tabulator key should still be held depressed, the said secondary latch 155 will be in the Figure 4 position and will prevent repeat tabulation, it being necessary to first release the depressed tabulator key to allow escapement of the tongue 54 from the secondary dog 155 on to the rear end of the lever 55. When the bail 42 is held under control of either of the latches, the rearward branches 40 of the reeds are clear of the bottom edges of the slides 61, 62, 63, and 64 so that the latter are freely movable under control of the tabulator keys and so that the restoration of the tabulator keys need not be effected before the conclusion of the tabulating run, that is, before the power restoration of the bail. Concomitantly with the restoration of the bail, the carriage is restored to the control of the escapement by the return of the lever 128 to normal position.

In certain classes of work, it is frequently desired to skip columns; and to expedite the work, the secondary latch 155 may be eliminated and the spring 156 directly connected to the latch lever 55, as illustrated in Figure 7. If this is done, the column-defining stops 27 will successively intercept the carriage in cooperation with the selected tabulator reed, the selected reed being automatically withdrawn and reprojected in response to each engagement of the reed by a stop 27, providing, of course, that the operated tabulator key is maintained depressed. In other words, the carriage will continue to move from column to column as long as the latch lever 55 is held in operated position by the tabulator key.

The three-armed member 131 is normally positioned so that its pendent arm 157 is in engage-

ment with an adjustable abutment 158, the latter of which is so adjusted that the upwardly branching arm 130 does not press the reeds together tightly, but merely crowds them loosely against the right end of the opening 37, the effect being that the reeds are freely projectable by their springs which, preferably, are very light. If, therefore, a reed in being projected collides head on with a set column stop 27, no damage will ensue even though the stop 27 may be of a rigidly supported kind. On the other hand, a settable stop, for example of the kind shown in the patent to Helmond No. 2,278,010, dated March 31, 1942, will not become unset. Under the circumstances just described, the projection of the reed follows after a slight movement of the carriage.

Describing now more in detail the operating train between the three-armed member 131 and the actuator 133, it will be noted from Figures 2 and 3, that the member 131 is pivotally carried on the rear wall 38 of the housing 36, and that the link 143 is guided near its upper end in an open slot 161 of the plate 32, the open side of the slot being closed by the bar 34 of the plate 32. The ball 146 is pivotally carried on the shaft 52 and its right end has a pin-and-slot connection 162 with the lever 147. The entire mechanism, 131 and 143 to 148, inclusive, is under the influence of a spring 163 which pulls upwardly on the lever 147 in front of the pivot rod 66 whereon said lever is pivoted. It should be understood that following the retraction of a reed 30, the lever 147 and its associated operating train are restored by said spring 163 and that the reeds 30 consequently again become crowded rightwardly. The bracket plate 58 and said lever 147 are in close adjacency and the latter is restricted against overthrow in either direction by two stop ears 164 projecting from the said bracket.

The hook-ended element 148 has a pin and slot connection 165 with the supporting lever 147, and is urged by a spring 166 forwardly and downwardly to occupy normally the position illustrated in Figures 1 and 2, a lug 167 on the element 148 being cooperative with the lever to limit forward motion of the hook-end of the element 148 and being posed normally over a projecting ledge 168 of the actuator 133.

Directing particular attention to Figures 1 and 2, it will be seen that the latch lever 55 is also operable under control of a tabulator key 171, which is disposed for convenient operation at the right end of the keyboard in front of type keys indicated at 172 (see Figure 1) by the palm of the operator's hand. This key comprises a lever including an upright arm 173 which is operative upon a pivoted member 174 overlying the extreme right end of the arm 126. Both the palm tabulator key 171 as well as said member 174 are riveted upon the right side wall of the machine and a spring 175 associated with said member serves to restore both said member and said key to their normal positions, as determined by the engagement of the lever against a boss 176 on the right side wall 10 of the machine. The operation of the palm key 171 is limited in a manner not shown. From the foregoing it is evident that operation of the palm key 171 causes the operation of the latch lever 55 and, consequently, the release of the ball 42 for upward displacement, as illustrated in Figure 6 in connection with a tabulator key 65.

The slides 61, 62, 63, and 64 are then in sole control over the reeds, inasmuch as the opera-

tion of the palm key 171 has no connection with said slides and leaves them undisturbed in their normal positions. Referring to Figure 8, it will be noted that all said slides are notched opposite the leftmost reed 30 and that every one of the other reeds is blocked against projection by at least one of the slides; wherefore, upon each depression of the palm key, only the said leftmost reed is free to rise to tabulation-controlling position. Of course, the slides, if desired, may be notched opposite any other reed instead of the leftmost one, in which case at the operation of the palm key 171 such other reed would become projected. The above-described palm key tabulating mechanism may be omitted entirely from the machine, and the leftmost notch on the slide 61 narrowed to block the reed normally but to release it upon depression of the leftmost tabulator key 65. Tabulating operations effected under control of the palm key are terminated in the same manner as those effected under control of the regular tabulator keys 65, such termination, of course, involving always the automatic retraction of the projected reed.

Typewriting machine carriages are usually provided with left and right margin stops 177, 178, respectively, which cooperate with frame-supported counterstop means to restrict typewriting between desired margins. The counterstop means in the present machine comprises a lever 181 which is swingable about a pivot stud 182 to a limited degree as defined by the aperture 183 in the top plate of the housing 36. The lever 181 may constitute a part of a power-carriage-return controlling mechanism of which a portion is indicated by the reference character 184 and which is fully disclosed in the patent to Helmond No. 2,262,676, dated November 11, 1941, and need here not be described. A spring 185 urges the lever 181 rightwardly to normally occupy the position indicated in dot-and-dash lines in Figure 11. At the approach of the line-end, the margin stop 178 engages and displaces the upper end of the lever 181 causing the lever to move to the full-line position of the same figure. The movement thus imparted to the lever 181 is utilized to bring about an operation of the actuator 133 to assure that no tabulator reed be in a projected position when the line end is reached, and thereby to render the carriage returnable without interference. Obviously, if a tabulating run is foreshortened under control of the line-end margin stop 178, there ensues no tabulation-terminating displacement of the projected reed, and consequently no retraction of such reed as a result of such displacement. For bringing about the operation of the actuator 133, a rightwardly extending arm 186 of the lever 181 underlies the rear end of the lever 147 and operates the latter incidental to the carriage reaching the line-end position as defined by the margin stop 178. See Figure 11. This brings about a transitory connection of the actuator 133 with the fluted shaft 132, resulting in a power retraction of the projected reed. In view of the fact the carriage may remain in line-end position for some time, it follows that the lever 181 may also remain operated. However, repeat operation of the actuator 133 is frustrated since the actuator edge 168 returns along a line above the hook face of the member 148, the latter becoming slightly displaced rearwardly against the tension of said spring 166. It is thus evident that the member 148 will only bring about another operation of the actuator 133 by a new actuation of the lever 181.

As seen in Figure 11, the pivot stud is located in a substantially vertical slot 187 of the lever 181, and the spring 185 is so disposed that the lever 181 pivots normally about the lower end of the slot. When it is desired to type beyond the margin defined by the line-end stop 178, the lever 181 is lowered by operation of a margin-release mechanism which may include a forked arm 188 associated with a pin 191 below the pivot stud 182. The margin-release mechanism is fully shown in the said patent to Helmond and includes a margin-release key, not shown, in the present drawings, which, when operated, lowers the said lever 181 below the margin stop 178 through the medium of said forked arm 188. Thus, it is possible to move or tabulate the carriage beyond the position defined by the line-end margin stop, as far as the absolute traveling limit of the carriage. In any case the carriage must be free for returning if the absolute line-end limit is reached. To this end, as seen in Figure 12, a permanent stop 192 is provided at the right end of the row of tabulator stops 27 and presents in the line-end limit position of the carriage, a rounded cam edge 193 in the projecting path of the reed 30 of the lowest denominational order, so that if the units of cents key 65 or the palm key 171 is operated, the said reed, in being projected, will be cammed leftwardly and will cause a power operation of the actuator 133 and consequently a reed-retracting motion of the bail 42. Should the operator, in this absolute line-end position, operate any of the other tabulator keys 65, the bail 42 will be freed and the proper slide or slides operated, but all the reeds will be blocked against projection by a rightward extension 194 of the stop 192. The said stop extension 194 maintains the said reeds 30 low enough so that the slides 61, 62, 63, and 64 can return freely to their normal positions upon the release of the operated tabulator key. Therefore, it will be seen that if any one or more tabulator keys are operated with the carriage in absolute line-end position, the carriage will be nevertheless free for return movement substantially as though no tabulator key had been operated. Of course, the operator may operate a tabulator key while the carriage is in a position a few letter-feed spaces leftward of the absolute line-end; and in such event, the resulting projected reed will be displaced leftwardly by its encounter with the stop 192 during the travel of the carriage in the same manner as outlined in connection with the column-defining stops 27, and the projected reed will be automatically withdrawn.

It is desirable to suppress typing, carriage return and other operations, while tabulating operations are in progress; and to this end, the latch lever 55 has a nose 195 which enters between two of a series of shiftable elements 196 whenever any of the tabulator keys 65, 171 are operated. The said series of elements are movably disposed between two abutments, not shown, and the said nose 195, when moved between the said two elements, crowds the elements oppositely and thereby locks the type keys, as also the carriage-return tripping mechanism, against operation, in a manner well known in the art but not shown. By virtue of the lever 55 remaining operated throughout the tabulation, the said nose 195 remains between the said elements throughout the tabulating operation, independently of the release of the tabulator key. On the other hand, the operation of any type key, or the tripping of the

carriage-return mechanism crowds the elements 196 directly associated with said nose 195 so that the reeds 30 are then unprojectable.

In Figure 13, there is shown a modified controlling mechanism for the reeds 30, which mechanism may be preferable to the permutational controlling mechanism hereinbefore described, particularly when only a few tabulator keys are employed or when the machine to which the invention is applied, provides ample room for accommodation of a full complement of individual controlling connections from the tabulator keys to the projectable stops or reeds 30. In Figure 13, such parts, which function and are substantially the same as hereinbefore described, are designated by the same reference characters as have hereinbefore been assigned to them. Instead of the aforesaid permutational mechanism, there is provided a set of tabulator key levers 197, one for each reed 30, which levers may be pivoted on a common frame-supported pivot rod 198 at some distance below the reeds. Each lever has rising from the said pivot rod an upright arm 201 ending in a hook 202 overlying one of the ledges 45 of the reeds 30. The ledges 45 are normally in contact with the bail 42 but are slightly spaced from the said hook ends 202. Individual springs 203 resiliently maintain the said key levers 197 in their normal positions wherein their forward portions are in contact with a stop plate 204. Each of the key levers 197 has a nose 205 overlying a pivoted bail 206, the latter of which may have said latch lever 55 integrally formed therewith at one end. The unitary structure 35 comprising the lever 55 and the bail 206 is resiliently maintained in the illustrated normal position by the aforementioned spring 156. Upon operation of any one of the tabulator key levers 197, the said bail 206 and associated lever 55 become actuated with the result that the arm 53 is freed for forward movement, wherefore the bail is consequently freed for upward movement. Concomitantly, as the bail 42 is freed, the operated key lever hook 202 moves forwardly of the ledge 45 of the associated reed so that this reed will become spring projected. Upward displacement of the bail 42 causes the release of the escapement in the manner previously described, and a tabulating run of the carriage ensues which becomes terminated responsive to the engagement of a column stop with the projected reed, the reed being then automatically retracted by an automatically instigated power restoration of the bail 42, in the same manner as hereinbefore described.

In both embodiments of the invention shown, the bail 42 is normally in latched position and the reeds 30 bear resiliently upwardly against the bail, but have some clearance with the lower edge 60 of the notched control slides 61, 62, 63, and 64, thereby to allow free reed selecting movement of the latter. Although such construction is desirable, it is obviously not an essential part of the invention and the bail need not be latched normally to hold the reeds.

In Figure 1 the tabulator key of the lowest denominational order is at the left and the other tabulator keys are rightwardly thereof, in progressively higher denominational orders. Such arrangement of the keys is conventional, but reverse to the denominational order in which typed amounts appear on the work sheet. Therefore, some typists prefer the tabulator keys to be in reverse to the order shown in the drawings. Their preference can be satisfied by a mere relocation

of the keys in the order desired and by correspondingly re-locating the notches 100 in the plates 81, 82, 83, and 84.

The invention has been described herein with reference to the details of construction shown but is capable of embodiment in different forms and certain features thereof are susceptible for use without others. Furthermore, although the invention has been described in association with a particular form of a typewriting machine, it is applicable to other typewriting machines; such as, for example, to flat-platen machines wherein tabulator keys are usually supported on a carriage supporting the typing mechanism.

The scope of the invention is as indicated in the following claims:

1. In a typewriter having a plurality of tabulating stops individually projectable for differentially arresting a carriage in ensuing tabulating runs; spring means adapted to project said stops, and means to render said stops restored and to detain them selectively releasable for projection by said spring means, said rendering means including a normally ineffective power device, common to all said stops, being responsive to the tabulating arrest of the carriage by any projected stop to retract any such stop.

2. In a typewriting machine having a carriage member movable on a frame member, a tabulating mechanism comprising, stop means on one of said members, a stop on the other member projectable into tabulation terminating range with said stop means, means constantly urging projection of said stop, an operable element, and means normally blocking said stop against movement into said range, responsive to the operation of said element to allow projection of said stop, and responsive to tabulation terminating engagement of said stop means with said stop to render the latter retracted.

3. In a typewriting machine having a carriage member adapted for tabulating movement on a frame member, the combination with stop means on one of said members, of a plurality of tabulating stops mounted on the other member for individual projection into tabulation controlling range with said stop means, means urging projection of all said stops, means for selectively controlling projection and for effecting retraction of said stops, selectively conditionable to free any desired stop for projection by said urging means, said controlling means including power means common to all said stops and responsive to tabulation terminating engagement of any projected stop with said stop means, to retract any projected stop.

4. In a typewriter having a plurality of tabulating stops individually projectable for differentially arresting a carriage in ensuing tabulating runs, spring means adapted to project said stops, normally ineffectively conditioned means for imparting tabulating motion to the carriage, and means to render said stops restored and to detain them selectively releasable for projection by said spring means, said rendering means including, key-responsive means to release said stops selectively to the influence of said spring means and to render said imparting means concomitantly effective, and means responsive to the termination of the tabulation under control of any projected stop to render said imparting means ineffective and concomitantly to retract the projected stop.

5. In a machine having a carriage adapted to execute tabulating runs, a plurality of tabulating

stops selectively projectable for variably controlling the extents of the tabulating runs, and means to project and retract said stops, comprising, means urging projection of every one of said stops, means normally blocking all said stops against projection, but being selectively conditionable to unblock any one of said stops for projection by said urging means, normally ineffective power means universal to all said stops for retracting them, and means to call said power means automatically into operation in consequence of the carriage approaching the end of the tabulating run.

6. In a machine having a carriage adapted to execute tabulating runs, a plurality of tabulator stops individually projectable for variably controlling the extents of the tabulating runs, means urging projection of said stops, means universal to said stops and movable from and to a normal position respectively to allow projection and to effect retraction of said stops, blocking means for said stops selectively operable to block all but a desired one of said stops against projection, and power means responsive to the selective operation of said blocking means to move said universal means from said normal position, and effective automatically in consequence of the carriage approaching the end of its tabulating run to move said universal means to said normal position, whereby responsive to the selective operation of said blocking means a selected stop will be projected by said urging means and whereby any so projected stop is automatically power-retracted at the end of the tabulating run of the carriage.

7. In a machine having a carriage adapted to execute tabulating runs, a plurality of tabulator stops selectively projectable for variably limiting tabulating runs, means urging projection of said stops, keys, means, normally blocking said stops against projection, selectively conditionable by operation of said keys to unblock desired stops for projection by said urging means, means universal to said stops movable from one to another position to retract said stops, power means, means automatically operative in consequence of the carriage approaching the end of its tabulating run, to cause said power means to move said universal means from said one to said other position, and means to hold said universal means in said other position at least pending the restoration of said keys.

8. In a machine having a plurality of tabulator stops individually projectable for carriage arresting operations, means urging projection of said stops, parts individual to said stops for normally blocking them against projection, means associated with said parts for operating them selectively to nonblocking position for projection by said urging means, means universal to said stops movable from one to another position to retract said stops, motor operable means responsive to the interception of the carriage by any projected stop to move said universal means from said one to said other position, and means to hold said universal means in said other position at least pending the restoration of said keys.

9. In a machine having a carriage adapted to execute tabulating runs, a tabulator stop projectable for limiting tabulating runs, and normally ineffective means adapted to propel the carriage for tabulating; spring means tending to project said stop, means operable to and from a normal position respectively to effect retraction of said stop, and to allow projection of said stop

by said spring means, means operable to and from normal position to render said propelling means respectively ineffective and effective, a key, and means for power operating both said operable means conjointly from their normal positions to their operated positions in response to the operation of said key, and from their operated to their normal positions automatically in consequence of the carriage approaching the end of the tabulating run.

10. In a typewriting machine having a carriage member adapted to execute tabulating runs on a frame member, the combination with a stop element on one of said members, of a plurality of denominational stops on said other member, individually projectable into tabulation controlling range with said stop element, and upon projection being slightly displaceable by engagement with said stop element during an ensuing tabulating run of the carriage, means acted upon when any denominational stop is displaced, and a power device common to all said stops and responsive to the said last means when acted upon, to retract automatically any projected denominational stop.

11. In a typewriting machine having a carriage member adapted to execute tabulating runs on a frame member, the combination with a stop element on one of said members, of a tabulator stop on the other member projectable into tabulation controlling range with said stop element, and upon projection being slightly displaceable by engagement with said stop element during an ensuing tabulating run of the carriage, an electric motor, means acted upon by said tabulator stop becoming displaced, and means responsive to the said last means when acted upon, to cause retraction of the tabulator stop by the power of said motor.

12. In a machine having a carriage member adapted to execute tabulating runs on a frame member, the combination with stop means on one of said members, of a stop on the other member projectable into tabulation limiting range with said stop means, power means including a constantly driven power device and actuator means transitorily connectable with said power device, to bring about the retraction of said stop, and means to effect automatically a transitory connection of said actuator means with said power device in consequence of the carriage member approaching the end of its tabulating run.

13. In a machine having a carriage member adapted to execute tabulating runs on a frame member, the combination with a stop element on one of said members, of a tabulator stop on the other member projectable into tabulation limiting range with said stop element and upon projection being slightly displaceable by engagement with said stop element during an ensuing tabulating run of the carriage, power means including a constantly driven power device and actuator means connectable transitorily with said constantly driven power device, to bring about the retraction of said tabulator stop, and means acted upon by said tabulator stop becoming displaced to connect transitorily said actuator means with said constantly driven power device.

14. In a machine having a carriage adapted to execute tabulating runs, a stop projectable to cause interception of the carriage for terminating tabulating runs, means urging projection of said stop, operable means, means normally blocking said stop against projection and conditionable by operation of said operable means to allow projection of said stop, motor drive

means conditionable for power-retracting said stop, and automatically operative means to condition said motor drive means for power-retracting said stop in consequence of the carriage approaching the end of its tabulating run.

15. In a typewriting machine the combination with a tabulating-carriage, a plurality of tabulating stops, which are selectively projectable for causing carriage interception at different positions, and means for causing tabulating travel of said carriage substantially while any stop remains projected; of means for so mounting the said stops that any stop upon being projected is capable of some yielding displacement as the carriage is being intercepted, an element acted on responsive to the displacement of any stop, an electric motor, and means common to all said stops and responsive to the said element when it is acted on to cause automatic retraction of any projected stop by the power of said motor.

16. The combination with a typewriter, having a carriage member movable on a frame member, of a tabulating mechanism, comprising, a series of denominational tabulator stops, including one of lowest denominational order, abutting each other and supported on one of said members so that they are individually projectable into tabulation stopping range with said other member, and also so that the tabulation stopping engagement of any stop with said other member results in a displacement of the said lowest order stop on its supporting member, in a direction parallel to the carriage, means to project said stops selectively and to retract them automatically following tabulation terminating engagement, including power means common to all said stops and responsive to the said displacement of said lowest-order stop to retract any projected stop.

17. In a typewriting machine having a carriage member adapted for tabulating movement upon a frame member, the combination with stop means on one of said members, of a plurality of denominational stop blades supported on the other member and selectively operable to project stopping ends thereon into tabulation controlling range with said stop means, means for so swingably mounting said blades that their stopping ends are movable substantially in parallel to the direction of carriage movement, said blades normally abutting each other near their stopping ends and said mounting means including spaced abutment means wherebetween said blades are restricted to swing limitedly, means resiliently crowding said blades in such direction against said abutment means so that any projected blade is capable of receiving a limited swinging movement through tabulation terminating engagement with said stop means, and so that said crowding means is adapted to be acted upon by all said blades, and means responsive to said crowding means being acted upon, to retract any projected blade.

18. In a machine having a carriage member adapted to traverse a frame member, the combination with stop means on one of said members, of a plurality of denominational stop elements on the other member disposed substantially in planes extending transversely to the carriage and movable to project stopping ends thereon into tabulation controlling range with said stop means, means for so mounting said elements as to render them displaceable at said stopping ends by tabulation stopping engagement with said stop means, about locations distant from said stopping ends, means for resiliently urging individual pro-

jection of said stops, means associated with said stop elements in the region of the said locations to control selectively projection of said stops by said urging means, and means to retract any projected stop in response to its displacement by tabulation stopping engagement with said stop means.

19. In a typewriting machine having a carriage member adapted for tabulating movement on a frame member, the combination with a stop element on one of said members, of a plurality of tabulator stops on said other member individually projectable thereon into tabulation controlling range with said stop element, means rendering said tabulator stops projectable to positions from which they are displaceable through engagement with said stop element during tabulating movement of the carriage, said rendering means including means resiliently opposing said stops against displacement, means acted upon when any of said tabulator stops is being displaced, and means common to all said stops and responsive to the said last means being acted upon, to retract automatically any projected tabulator stop.

20. In a typewriting machine having a carriage member adapted for letter-feeding and tabulating movement on a frame member, the combination with a stop element on one of said members, of a plurality of tabulator stops on said other member individually projectable into tabulation controlling range with said stop element, means constantly tending to impart tabulating movement to said carriage, letter-feeding means normally in control of the carriage, means to release said carriage from the control of said letter-feeding means concomitantly with the projection of any one of said tabulator stops, wherefore said carriage tabulates when any tabulator stop is projected, means for so mounting said tabulator stops that any one upon projection is yieldingly displaceable by engagement with said stop element as they cooperate to intercept the carriage, means acted upon when any of said tabulator stops is displaced, and means common to all said tabulator stops and responsive to the said last means when acted upon, to retract automatically any projected tabulator stop and to restore said carriage to the control of said letter-feeding means.

21. In a typewriter having a plurality of tabulating stops individually projectable for arresting a carriage in ensuing tabulating runs; spring means adapted to project said stops, key-operable means selectively operable to block all but desired ones of said stops against projection, a member common to all said stops, movable to a certain position to retract said stops, means for releasably detaining said member automatically whenever moved to the said position, said detaining means being responsive to each operation of said key-operable means to free said member, whereby said stops become selectively projected upon operation of said key-operable means, and means responsive to the conclusion of each tabulating run, to power-move said member to the said position.

22. In a typewriting machine having a plurality of tabulating stops individually projectable for arresting the carriage in ensuing tabulating runs; spring means adapted to project said stops, a member universal to the said stops movable to retract said stops, latch means for automatically holding said member upon stop-retracting movement, means selectively conditionable to block all except the desired stop against projection, an

operative connection between said conditionable means and said latch means to release the latter upon conditioning of the conditionable means, whereby said stops are selectively spring projectable, a rotary drive element, actuator means adapted by transitory engagement with said drive element to impart a stop-retracting movement to said member, and means responsive to the completion of each tabulating run to transitorily engage said actuator means with said element.

23. In a typewriting machine having a carriage member movable on a frame member, the combination with stop means on one of said members, of a plurality of tabulating stops mounted on the other member for individual projection into tabulation terminating range with said stop means, means constantly urging projection of said stops, means movable oppositely respectively, to allow projection of said stops and to retract said stops, means to hold said movable means upon stop retracting movement, means selectively conditionable to block all but desired stops against projection, means operable to condition said last means selectively and concomitantly to release said holding means, said movable means being then freed and a desired stop becoming then projected, a constantly operating power member, an actuator mechanism transitorily connectable with said power member to effect a stop-retracting movement of said movable means, and means responsive to tabulation terminating engagement of any projected stop with said stop means, to connect said actuator mechanism for transitory stop-retracting operation by said power member.

24. In a typewriting machine having a carriage member movable on a frame member, the combination with stop means on one of said members, of a plurality of tabulating stops mounted on the other member for individual projection into tabulation terminating range with said stop means, means urging projection of said stops, means movable from one to another position to retract said stops and conversely movable to free said stops for projection, normally idle power means for moving said movable means to said other position, means to hold said movable means in said other position upon movement thereto, said holding means being operable to free said movable means, but adapted to hold it again when it is subsequently again moved to said other position, means selectively conditionable to block all but desired stops against projection, means operable to condition said last means selectively and concomitantly to operate said holding means, said movable means being then freed and a desired stop becoming then projected by said urging means, and means responsive to tabulation terminating engagement of any projected stop with said stop means, to cause said power means to be effective to effect stop retraction.

25. In a typewriting machine, the combination with a carriage tabulating mechanism comprising, a tabulator stop, key responsive means to project said stop to tabulation controlling position, an electric motor, and means connectable with said motor to power-retract said stop, of means to connect said connectable means with said motor responsive to the carriage reaching a certain line-end defining position, thereby to cause automatic power-retraction of said stop.

26. In a machine having a carriage member adapted to execute tabulating runs on a frame member, the combination with stop means on one of said members, of a plurality of denominational stop elements on the other member disposed sub-

stantially in planes extending transversely to the carriage and movable to project stopping ends thereon into tabulation limiting range with said stop means, means for so mounting said denominational stop elements as to render them displaceable at their stopping ends by tabulation limiting engagement with said stop means, about locations distant from said stopping ends, and power means including a constantly driven power device and actuator means connectable transitorily with said constantly driven power device through displacement of said stopping ends, to bring about a retracting movement for any stop element having its stopping end projected.

27. In a machine having a carriage member adapted to execute tabulating runs on a frame member, the combination with stop means on one of said members, of a stop on the other member projectable into tabulation limiting range with said stop means, a constantly driven power device, means transitorily connectable with said power device for operation thereby to retract said stop, and means to effect a transitory connection of said connectable means with said power device in consequence of the carriage member approaching the end of each tabulating run, said transitorily connectable means including a lost motion provision to delay retraction of the projected stop until after the carriage has been arrested by cooperation of the projected stop with the stop means.

28. In a machine having a carriage member adapted to be tabulated across a frame member, tabulator stops, representing columns supported on one of said members, a series of denominational selecting counterstops supported on the other one of said members and projectable individually into tabulation controlling range with said tabulator stops, means to impart tabulating motion to the carriage in response to projection of any counterstop, but effective to restrain the carriage against tabulating movement whenever all said counterstops are retracted, means urging individual projection of said counterstops, tabulator keys, means for blocking said counterstops against projection, being selectively operable by said keys to render any desired counterstop unblocked, said counterstops being supported on said other member in a manner to be limitedly displaceable by tabulation stopping encounter with any of said tabulator stops and so that upon retraction a displaced counterstop will escape the encountered tabulator stop in a direction opposite to said displacement, power means, retractor means for said counterstop movable from a normal to an operated position to allow projection of said counterstops and movable to said normal position to retract any projected counterstop, and means to cause said power means to move said retractor means from normal to operated position whenever any one of said keys is operated or is held operated while said retractor is in or arrives in normal position, and to cause said power means to move said retractor from operated to normal position responsive to the displacement of any projected counterstop by encounter with any one of said tabulator stops, whereby repeat tabulation can be obtained by sustained operation of any of said keys.

29. In a machine having a carriage member adapted to be tabulated across a frame member, tabulator stops, representing columns supported on one of said members, a series of denominational selecting counterstops supported on the other one of said members and projectable individually into

tabulation controlling range with said tabulator stops, means to impart tabulating motion to the carriage in response to projection of any counterstop, and to restrain the carriage against tabulating movement whenever all said counterstops are retracted, means urging individual projection of said counterstops, tabulator keys, means for blocking said counterstops against projection, said blocking means being selectively operable by said keys to render any desired counterstop unblocked, said counterstops being supported on said other member in a manner to be limitedly displaceable by tabulation stopping encounter with any of said tabulator stops and so that upon retraction a displaced counterstop will escape the encountered tabulator stop in a direction opposite to said displacement, means, normally suppressing movement of said retractor means from normal position, under control of said keys, to free said retractor means for movement from normal to operated position whenever any one of said keys is operated or held operated while said retractor is or arrives at normal position, normally ineffective power means, and means to render said power means transitorily effective to move said retractor from operated to normal position responsive to the displacement of any projected counterstop by encounter with any of said tabulator stops, whereby repeat tabulation can be obtained by sustained operation of any of said keys.

30. In a typewriter having a plurality of tabulating stops individually projectable for arresting a carriage in ensuing tabulating runs; spring means adapted to project said stops, key-operable means for blocking said stops individually releasable for projection by said spring means, power means normally blocking said stops collectively against projection, responsive to said key means to allow any selectively released stop to be projected by said spring means, and responsive to the termination of each tabulating run and also to the movement of the carriage to a line-end-defining position, to retract any projected stop.

31. In a typewriting machine having a carriage member movable on a frame member, in combination, a tabulating mechanism comprising, stop means on one of said members, a stop projectably supported on the other member for terminating tabulations by engagement with said stop means, and projecting and retracting means for said stop, said stop being projectable to a position from which it is displaceable on its supporting member through tabulation terminating engagement with said stop means, said projecting and retracting means comprising, motor means, means associative with said motor means for operation thereby to retract said stop, and means responsive to displacement of said stop by said stop means to associate said stop retracting means for operation by said motor means, and means for associating said retracting means and motor means also incidental to movement of the carriage to a line-end position, independently of said stop means.

32. In a typewriting machine having a carriage member movable on a frame member; means to tabulate said carriage member to different positions, comprising, a projectable and retractable tabulating stop on one of said members, and normally idle power means adapted to retract said stop; margin stop elements oppositely on said members engageable with each other to limit carriage travel at line ends independently of said tabulating stop, one of said elements being displaceable on its supporting member and being op-

erable by the other member at the approach of the line end, and means operable through the said displacement of one of the said elements, adapted to render said power means effective to retract the tabulator stop.

33. In a typewriting machine having a carriage member movable on a frame member, means for tabulating said carriage member to different positions, comprising a tabulating stop on one of said members projectable to and retractable from a tabulating controlling position, transversely to the travel of the carriage, and displaceable on its supporting member in a direction parallel to the travel of the carriage, operable means, and means responsive to said operable means to project said stop, and responsive to said displacement of said stop to retract the latter, another stop on the other one of said members having a cam face so disposed that, when the carriage is in an absolute line-end position, projection of the said tabulator stop will cause it to be cammed in the said direction, whereby, if the carriage is in said extreme line-end position, the said tabulator stop will be immediately retracted after projection.

34. In a typewriting machine having a plurality of individually projectable carriage-arresting stops; power means adapted to project said stops individually; and means operable to render said power means effective to project said stops, comprising, keys, a group of parallel motion devices, adapted for different permutatorial operation by said keys, and means adapted by said permutatorial operations of said parallel motion devices, to select said stops for operation by said power means.

35. In a typewriting machine having a plurality of individually projectable carriage-arresting stops; spring means tending to project said stops, and means blocking said stops selectively releasable for projection by said spring means, comprising fewer blocking elements than stops, adapted by selective permutatorial actuation to block all but a desired stop against the projecting influence of said spring means, tabulating keys distant from said blocking elements, an operating connection for each of said elements extending to the proximity of the said keys, and a permutating mechanism operable by said keys to actuate the said elements permutatively through the said connections, so that upon operation of each key a different stop will become released for projection by said spring means.

36. In a typewriting machine having a plurality of tabulating stops individually projectable to tabulation controlling positions, means urging projection of said stops, and means for selectively controlling projection of said stops by said urging means and for automatically effecting the retraction of said stops, said last means comprising,

ing, a plurality of blocking elements adapted by different permutatorial actuation to block all but a desired stop against projection, and power means automatically responsive to the tabulating arrest of the carriage by any of said stops to retract such stop.

37. In a typewriting machine having a plurality of stops individually projectable for arresting a carriage; spring means tending to project said stops, and means blocking said stops selectively releasable for projection by said spring means, comprising fewer blocking elements than stops, adapted by permutatorial actuation to release said stops selectively to the projecting influence of said spring means, tabulating keys distant from said blocking elements, an encased wire connection for each of the said elements extending to the proximity of the said keys, and a permutating mechanism operable by said keys to actuate the said elements permutatively through the said connections, so that upon operation of each key a different stop will become released for projection by said spring means.

38. In a typewriting machine having a plurality of individually projectable carriage arresting stops, means urging projection of said stops, means blocking said stops selectively releasable for projection by said urging means, comprising, a member movable from and to a normal position, respectively, to allow projection of said stops and to retract said stops, and a series of elements normally blocking all but a particular one of said stops against projection, being adapted by different permutatorial operations thereof to block all said stops except a desired one against projection, means to effect different stop-selecting permutatorial operations of said elements and to concomitantly cause said member to move from its normal position, wherefore a desired stop will then become projected, a key, and means responsive to said key to cause a movement of said member from said normal position to thereby cause a projection of the said normally unblocked stop.

39. In a machine having a carriage adapted to execute tabulating runs, a plurality of stops individually projectable for arrest of the carriage in different positions; power means for projecting said stops individually and for retracting them, means operable to render said power means selectively effective to project any desired stop, comprising fewer elements than said stops, adapted by different permutatorial operations thereof to select any one of said stops for operation by said power means, and means to render said power means automatically effective in consequence of the carriage approaching the end of its tabulating run, to retract any projected stop.

HARRY C. YAEGER.
